W. J. REILLY.

MATTING.

APPLICATION FILED MAR. 1, 1921.

1,408,828.

Patented Mar. 7, 1922.

Inventor
William J. Reilly
By his Attorney, *Reed and Kellogg*

UNITED STATES PATENT OFFICE.

WILLIAM J. REILLY, OF NEWARK, NEW JERSEY.

MATTING.

1,408,828.

Specification of Letters Patent. Patented Mar. 7, 1922.

Application filed March 1, 1921. Serial No. 448,806.

To all whom it may concern:

Be it known that I, WILLIAM J. REILLY, a citizen of the United States, residing at Newark, in the county of Essex and State 5 of New Jersey, have invented certain new and useful Improvements in Matting, of which the following is a specification, reference being had therein to the accompanying drawing.

10 My invention relates to improvements in matting and has particular reference to matting formed of links or small sections of material such as leather hinged together in continuous formation, forming strips or 15 runners such as are adapted for restaurants, halls, public places and the like. One of the principal objects of my invention is to provide a construction which is simple and inexpensive and which distributes the strain 20 in lifting and handling the mat so as not to develop weakness at any one particular point while at the same time providing sufficient rigidity and strength at all points.

In the accompanying drawings, I have 25 illustrated in Fig. 1 in plan view, parts being broken away, a suitable form of mat embodying an application of my invention. Fig. 2 is an end view looking upwardly at Fig. 1.

30 The small pieces of material of which the mat is made may be fluted or corrugated as indicated at 3 in Fig. 2, and are preferably perforated to receive the wires or rods 4 which are preferably bent at the ends in U- 35 shape formation as indicated at 5 terminating in loops or hooks 6 for engaging the next rod or wire as shown. At predetermined spaced positions a rectangular wire or rod such as indicated by the reference 40 character 7 may be provided and the free ends connected by a sleeve such as 8, the last or end piece being separated by smaller pieces of material such as 9 as shown.

In mats of this character heretofore used, 45 it has been customary to leave the intervening spaces such as 10 at the sides open with the result that in picking up a corner of the mat, undue strain has been developed along the side tending to bend and twist the coupling rods some times breaking them apart 50 and at other times leaving them buckled and bent so that the mat does not lay flat,

thus presenting an obstruction to trip over. By the construction hereinbefore described, this weakness in the mat is overcome, all of 55 the sections being securely bound together while at the same time sufficient flexibility is preserved to facilitate rolling up the mat. Furthermore, the sleeves or clinches such as 8 are greatly reduced in number and may in 60 fact if desirable be entirely eliminated, thus obviating another weak point in the construction of this type of matting as heretofore used.

Of course it will be understood that various modifications may be made in the construction and arrangement of parts without departing from the spirit of the invention as claimed.

I claim:

1. In a mat of the class described having U-shaped retaining rods, groups of solid links in staggered relation, the individual links of said groups secured face to face with their edges exposed, the ends of one 75 group overlapping the ends of an adjacent group, said overlapping ends pierced by one of said rods having loops at the free ends engaging the next adjacent rod thereto, and groups of said links intermediate of the 80 ends of said mat between which the adjacent ends of groups of links are secured by a U-shaped rod, both legs of which pass through said intermediate groups.

2. In a mat of the class described having 85 U-shaped retaining rods, groups of solid links in staggered relation, the individual links of said groups secured face to face with their edges exposed, the ends of one group overlapping the ends of an adjacent 90 group, said overlapping ends pierced by one of said rods having loops at the free ends engaging the next adjacent rod thereto, and groups of said links intermediate of the 95 ends of said mat between which the adjacent ends of groups of links are secured by a U-shaped rod, both legs of which pass through said intermediate groups, and rows of discs between the free ends of said groups at the end of said mat.

In testimony whereof I hereunto affix my signature.

WILLIAM J. REILLY.
